UNITED STATES PATENT OFFICE

JACOBUS DIRK HAAKER, OF EINDHOVEN, NETHERLANDS

SUNSHADE, UMBRELLA AND THE LIKE

Application filed November 11, 1930, Serial No. 494,855, and in the Netherlands February 24, 1930.

This invention refers to improvements in sunshades, umbrellas and the like of the telescope-type and for the sake of convenience these will hereinafter be referred to as umbrellas.

It has already been proposed to reduce the length of such articles when collapsed, by making the rods for supporting the fabric cover in the extended position in two parts, so that on collapse of the umbrella the one part of each rod can be slid into the other, tube-like part. With this construction, the fabric is, on collapse, tucked up over the said rods, whereby ease of injury results and the umbrella has an unpleasant appearance. Moreover, in practice it is difficult, so to arrange the frame of the umbrella that the latter can easily be handled.

The invention relates to a telescope-umbrella which does not present these disadvantages. According to the invention, the shaft of the umbrella is hollow and provided interiorly with a slider to which the fabric is fastened, so that the latter on collapse of the umbrella can partly be drawn into the shaft, either by a spring or by hand. Thereby the first mentioned difficulty is overcome. The second difficulty can be overcome according to the invention by connecting with the slider referred to, a second slider movable over the outside of the shaft; the said second slider and the upper end of the hollow shaft being connected respectively to parts of an extensible frame or scissor-like arrangement serving for the extension and collapsing of the fabric cover. The result is that to collapse the umbrella, the slider in the shaft is drawn further into the shaft so that the umbrella is simultaneously collapsed and telescoped.

The last mentioned embodiment of the invention is represented on the drawings wherein Figs. 1 and 2 are part sections showing the umbrella in erected position and in the semi-open position, respectively, while Fig. 3 is a view of the umbrella in the fully collapsed position.

In the tubular part 1 of the shaft a second tubular member 2 is provided into which the part 3 carrying the knob 4 of the handle

can be slid. Around the tube 1, a slider 5 is arranged which can be locked in its uppermost position by a spring catch 6 (Fig. 1) in the usual way. The slider 5 is provided with keys 7 which extend through slots in the tube 1 and are connected through a spring 8 with a second slider 9, to which the fabric is fastened. The inner tube 2 is closed at its upper end by means of a plug 11.

To the slider 5 and to a ring 12 fixed to the upper end of the tube 1 are fastened the parts 13 and 14, respectively, of an extensible frame or "scissors" arrangement 13-16 over which the fabric 10 (Fig. 1) is spread and to which it is fastened at the ends and, if desirable, also at other points of the members 16. The parts 13 and 15 of the extensible frame are conveniently double and the parts 14 and 16 single, whereby this frame in collapsed position occupies as little space as possible.

When the slider 5 is moved downwards, the extensible frame is collapsed. Thereby the fabric 10 is folded, but at the same time drawn into the tube 1 by the slider 9. The spring 8 provides for the necessary freedom in working. When the umbrella is fully collapsed, the central part of the fabric is enclosed by the tube 1. If thereafter the handle 3 is slid into the tube 2, the umbrella has about half the length of an umbrella of the usual type.

What I claim is:

1. A telescope-umbrella wherein the fabric is fastened at the centre to an element slideable within a tube portion of the shaft and adapted to be drawn into said tube portion.

2. A telescope-umbrella as set forth in claim 1 wherein the said slider is connected with a second slider mounted around said tube portion, elements of a collapsible lazy-tong frame being connected to said second slider and to the end of the tube portion, respectively, so that by means thereof the fabric cover can be extended.

3. A telescope-umbrella as set forth in claim 1 wherein the said slider is connected with a second slider by means of a spring, said second slider being mounted around said tube portion and elements of a collapsible

lazy-tong frame being connected to said second slider and to the end of the tube portion respectively, so that by means thereof the fabric can be extended.

- 5 4. A telescope-umbrella as set forth in claim 1 wherein a further tube is provided within the tube portion of the shaft, into which further tube the other portion of the shaft can be slid.
- 10 5. A telescope-umbrella as set forth in claim 1 wherein a further tube is provided within the tube portion of the shaft, into which further tube the other portion of the shaft can be slid, the free end of the tube 15 portion of the shaft being reduced to the diameter of the enclosed tube and said other portion of the shaft being provided with a handle or knob adapted to be slid over said reduced end.

200 In testimony whereof I affix my signature.

JACOBUS DIRK HAAKER.
